COMPACTION APPARATUS

William A. Herpich and Henry C. French, Jr., Knoxville, Tenn., assignors to Dempster Brothers, Inc., Knoxville, Tenn., a corporation of Tennessee

Filed June 10, 1959, Ser. No. 819,457

5 Claims. (Cl. 91—169)

This invention relates to compaction apparatus and more particularly to hydraulic equipment for mobile compaction bodies of the type employed in the handling of refuse and the like.

In the handling of trash and refuse of various kinds, the use of truck mounted compaction bodies has proved to be very advantageous. The truck may be driven from one refuse accumulation station to another, and at each station, refuse may be loaded into the body and compacted so that it will occupy a relatively small volume. Then, when the body is filled with compacted refuse, the truck may be driven to a dump where the refuse may be discharged from the body.

Compaction bodies of this type usually include a large refuse chamber extending longitudinally of the body. The rear end of the chamber is closed normally by a rear door, but such door may be opened when it is desired to discharge the compacted refuse from the chamber. The front end of the refuse chamber is bounded by a movable wall or packer head mounted in the body for longitudinal movements and driven by suitable hydraulic equipment.

Refuse may be loaded into the refuse chamber through the top of the body at a location near its front end. Then, the packer head is caused to move rearwardly to compress and pack the material into the rear end portion of the chamber. After the packing stroke of the packer head, the packer head is moved forwardly to condition the apparatus for the reception of another load of refuse through the top of the body.

This cycle normally is repeated at a number of different collection stations before the refuse chamber becomes so full that it must be discharged.

The present invention is concerned primarily with hydraulic equipment for manipulating the packer head of a compaction body. It is a general object of the invention to provide improved hydraulic means which will cause the compaction apparatus to function more efficiently and with less attention from the operator of the apparatus.

A more specific object of the invention is to provide an improved telescopic cylinder which can be retracted quickly and easily, so that it will be possible to reduce the time required for the forward or idle stroke of the packer head of a compaction body and so that the power consumed in this idle stroke will be reduced.

Another object of the invention is to provide an improved telescopic cylinder in which the power available at the commencement of a retraction stroke is greater than that available at any other time during the retraction stroke. With this construction, the force necessary for setting the parts in motion initially is available readily.

Yet another object of this invention is to provide automatic control means for causing the packer head to move through a complete compaction cycle without requiring any attention from the operator of the apparatus.

Another object of the invention is to provide a hydraulic system of such a construction that a single telescopic cylinder serves not only to move the packer head but also to detect the degree of compression of the compacted material, so that the automatic control means requires no separate detector element.

The foregoing objects may be accomplished, according to the invention, by providing a compaction body with a

2

double-acting, multiple stage, hydraulic cylinder for moving the packer head back and forth, and by providing novel means for controlling the flow of hydraulic fluid with respect to the cylinder.

5 In the preferred embodiment of the invention, the double-acting hydraulic cylinder is so constructed that the hydraulic fluid for both extending and retracting the cylinder enters and leaves the cylinder through the plunger end, that is, the small end of the cylinder. Compaction 10 of the load in the body is accomplished when the cylinder is extended to push the packer head rearwardly. This power stroke requires a rather large volume of hydraulic fluid, and in order that the fluid may flow as freely as possible, the passageways within the cylinder for this 15 fluid are relatively large. In contrast, only a small amount of power is required for the retraction of the packer head, and the oil passages in the cylinder for directing the fluid so as to retract the cylinder may be relatively small.

20 It is particularly important that the oil passageway through which oil may flow out of the cylinder during retraction be free from obstructions. This has not been the case in the telescopic cylinders used heretofore in 25 compaction bodies, and as a result the retract or return stroke of the packer head has always taken a substantial amount of time. Moreover, the back pressure in the hydraulic fluid causes unnecessary power losses. The present invention overcomes these difficulties by a novel arrangement of the flow passages within the hydraulic 30 cylinder.

The basic cycle of operations for the compaction body includes a rearward movement of the packer head, a forward movement of the packer head, and an idling period during which a new charge of refuse may be inserted into 35 the body. The length of the rearward stroke of the packer head varies in accordance with the amount of material in the body itself. That is to say, the packer head will move further when there is very little material in the body than when the body is nearly full. The controlling factor is the degree of compression of the material. The packer head moves rearwardly until the back pressure of the charge reaches some predetermined value. At this point, the compression stroke of the packer head 45 is terminated, and the packer head is moved forwardly again toward the front end of the body.

The present invention contemplates a control mechanism by which an entire cycle of packer head operation 50 may be carried out automatically. After a body of refuse has been inserted into the body, the operator trips the control mechanism manually, and then the control mechanism takes over to direct the hydraulic fluid along paths which will cause the telescopic cylinder to extend until 55 a predetermined back pressure is reached, and then move forwardly to the front end of the body, where it remains at rest until the operator of the equipment again trips the control mechanism.

60 This feature of the invention makes it unnecessary for the operator of the equipment to utilize his judgment as to how far the packer head should go during each compaction stroke and it also makes more time available to the operator for the accomplishment of his tasks. After the operator has tripped the control mechanism, he may 65 leave the compaction body entirely to collect more refuse to be dumped into the body. While he is gone, the apparatus automatically goes through the compaction and the retraction strokes and comes to rest in the proper position.

70 A better understanding of the structure and operation of the invention will be gained from a study of the fol-

lowing detailed description of certain embodiments there-of illustrated in the drawings, in which:

FIG. 1 is a side elevational view of a truck-mounted compaction body for handling refuse;

FIG. 2 is a longitudinal cross sectional view of a three stage, double acting, hydraulic cylinder unit for use in the compaction body of FIG. 1, showing the positions of the various parts when the cylinder unit is retracted;

FIG. 3 is a longitudinal cross sectional view of the cylinder unit shown in FIG. 2, but illustrating the positions of the various parts when the cylinder unit is expanded;

FIG. 4 is a transverse cross sectional view taken along the line 4—4 in FIG. 3;

FIG. 5 is a diagrammatic view of the hydraulic system for operating the hydraulic cylinder unit connected to the packer head of the apparatus;

FIG. 6 is an elevational view of an automatic control valve used in the system of FIG. 5;

FIG. 7 is a longitudinal cross sectional view of the control valve, taken along the line 7—7 in FIG. 6 and showing the parts in the positions they assume when the hydraulic cylinder unit is idle;

FIG. 8 is a view similar to FIG. 7, but showing the parts in the positions they assume when the hydraulic cylinder unit is being expanded;

FIG. 9 is a cross sectional view similar to FIGS. 7 and 8, but illustrating the parts in the positions they assume when the hydraulic cylinder unit is being retracted;

FIG. 10 is a vertical cross sectional view of the control valve, taken along the line 10—10 in FIG. 9;

FIG. 11 is a vertical cross sectional view of the control valve, taken along the line 11—11 in FIG. 9;

FIG. 12 is a longitudinal cross sectional view of another form of double acting hydraulic cylinder unit which may be used in the compaction body of FIG. 1, showing the parts in the positions they occupy when the cylinder is expanded; and

FIG. 13 is a longitudinal cross sectional view of the top half of the cylinder unit of FIG. 10, showing the parts in the positions they occupy when the cylinder is retracted.

The refuse handling equipment illustrated in FIG. 1 of the drawings is in the form of a truck 2 having a frame 4, wheels 6, a cab 8, and a refuse body 10. The apparatus also may include a front end loading mechanism 12 for raising detachable refuse containers 14 over the cab 8 and dumping them into the body 10.

Disposed within the body 10 is a packer head 16 mounted for longitudinal movements relative to the walls of the body 10. This packer head 16 actually forms the front wall of the refuse chamber in the body 10. Movements of the packer head 16 are brought about through operation of a hydraulic cylinder unit 18 pivotally connected at 20 to the body 10 and pivotally connected at 22 to the packer head 16. Upon expansion of the hydraulic cylinder unit 18, the packer head 16 moves rearwardly of the body 10 to compress or pack any material in the body between its rear face and the rear door or wall of the body 10.

The normal sequence of operations performed by the apparatus shown in FIG. 1 will be evident. First, the operator drives the truck 2 to the location of a detachable container 14 which is to be emptied. The loader mechanism 12 lifts the container 14 to dump its contents into the body 10 rearwardly of the packer head 16, and then returns the container 14 to the ground. The charge is compacted to the desired degree by moving the packer head 16 rearwardly until a predetermined back pressure is built up in the compressed charge. A return, or forward, stroke of the packer head 16 conditions the apparatus for the reception of the next charge.

This basic cycle may be repeated many times before the body 10 is filled to such an extent that it must be emp-

5 tied. When it is desired to empty the body 10, the vehicle is driven to a dump or the like, the rear door of the body 10 is opened, and the packer head 16 is moved all the way to the rear of the body 10 so as to eject the material through the rear door of the body.

It will be observed that useful work is accomplished by the packer head 16 only during rearward strokes thereof. Both compaction and ejection take place as the packer head 16 moves rearwardly. Forward strokes or movements of the packer head 16 are idle strokes which serve merely to position the head 16 properly for the beginning of a new working cycle. Nevertheless, these "idle" strokes of the packer head are brought about through the development of relatively high pressures in the hydraulic system. It is desirable that these forward strokes of the packer head 16 be carried out quickly and with a minimum consumption of power.

It also will be observed from FIG. 1 that the rearward strokes of the packer head 16 are brought about by expansion of the hydraulic cylinder unit 18, whereas the forward strokes of the packer head 16 are brought about by contraction of the cylinder hydraulic unit 18. In order that the hydraulic system may function rapidly and with small power losses during the retraction of the cylinder unit 18, this cylinder unit 18 has been provided with a novel arrangement of internal flow passages best illustrated in FIGS. 2, 3 and 4.

The cylinder unit 18 includes three cylinders 24, 26, and 28. The largest of these, i.e., cylinder 24, sometimes is referred to as the body of the unit. The smallest cylinder 28, on the other hand, is sometimes referred to as the ram or plunger of the unit.

The large cylinder 24 is closed at one end by a wall 30. At its other end, the large cylinder 24 is threadedly connected to an annular retainer 32 which extends inwardly and serves to position a suitable bushing 34 located between the inner surface of the cylinder 24 and the outer surface of the cylinder 26. The interior wall of the cylinder 24 is recessed at 36 for receiving an O-ring device 38 which forms a stop for a spacer 40 located between the cylinders 24 and 26 and having an annular undercut portion 42 on its interior surface providing a longitudinally extending oil passage or duct therein. A body of suitable packing material 44 preferably is located between the spacer 40 and the bushing 34.

The intermediate cylinder 26 also is provided with a retainer 46, a bushing 48, a spacer 50 having a longitudinal oil passage or duct 52, an O-ring device 54 and a body of packing material 56. These components are similar to those carried by the larger outer cylinder 24.

At its innermost end, the intermediate cylinder 26 has secured thereto a piston member 58. The piston member 58 slides back and forth with respect to the large cylinder or body 24 during expansion and retraction of the unit 18. Sealing rings 60 preferably are carried by the piston member 58 in the customary manner.

The smallest cylinder or ram 28 also is provided with a piston member 62 at its forward end. The piston member 62 carries the usual sealing rings 64 and slides back and forth with respect to the intermediate cylinder 26 during operation of the unit 18. The outer end of the ram 28 is substantially closed by a member 66 and a fitting 68 secured thereto. These elements are provided with oil passageways 70 and 72 which communicate respectively with conduits 74 and 76.

70 75 Mounted within the ram cylinder 28 is an adapter member 78 having a large longitudinal oil passageway 80 and having also a radial oil channel 82. The oil channel 82 is isolated from the main portion of the interior of the cylinder 28 by suitable sealing rings 84 contacting the interior wall of the cylinder 28. Oil may enter the channel 82 through a pipe 86 secured to the members 66 and 68 and communicating with the passage 72. It is preferred that an oil seal 88 be provided between the pipe 86 and the adapter 78. A retaining ring 90 may be

employed to hold the adapter 78 in position with respect to the cylinder 28.

When it is desired to expand the unit 18 from the condition shown in FIG. 2 to the condition shown in FIG. 3, oil is forced into the unit 18 through the conduit 74 and the passage 70. It may pass readily from one end of the ram 28 to the other through the large opening 80 in the adapter 78, so that the interior of the unit 18 will be filled rapidly. The oil then forces the cylinders 24 and 26 outwardly with respect to the innermost cylinder 28. This motion causes the packer head 16 of the apparatus shown in FIG. 1 to move rearwardly.

When it is desired to retract the unit 18 from the condition illustrated in FIG. 3 and bring it into the condition illustrated in FIG. 2, oil is forced into the unit through the conduit 76 and the passage 72. From the passage 72, the oil flows through the pipe 86 and into the radial channel 82 in the adapter 78. From the channel 82, the oil may flow through an aperture or port 92 in the wall of the cylinder 28.

With the cylinder unit 18 in the extended position shown in FIG. 3, the port 92 communicates with the longitudinal duct 52 in the spacer 50 carried by the end portion of the intermediate cylinder 26. This permits oil to flow into the space between the spacer 50 and the piston 62. Since the piston 62 is fixed to the ram 28 and the spacer 50 is fixed to the intermediate cylinder 26, the ram 28 and the intermediate cylinder 26 move relative to each other under the influence of the pressure of the oil passing through the relief or duct 52 in the spacer 50. This relative movement continues until the piston 62 on the ram 28 is brought into abutting relationship with respect to the piston 58 on the intermediate cylinder 26.

Just before the pistons 58 and 62 contact each other, however, the relative movement between the ram 28 and the intermediate cylinder 26 brings the piston 62 on the ram 28 beyond a port 94 in the wall of the intermediate cylinder 26. This relationship is indicated best in FIG. 2 of the drawings. After the port 94 has been brought into communication with the port 92, the oil from the inlet conduit 76 may flow into the relief or longitudinal channel 42 in the spacer 40 carried by the large cylinder or body 24 of the unit 18.

Again it will be observed that the oil pressure acts upon a piston 58 carried by the intermediate cylinder 26 and a spacer 40 carried by the outer cylinder 24 to cause relative movement between the intermediate cylinder 26 and the large cylinder 24. This movement continues until the piston 58 on the intermediate cylinder 26 abuts against the end wall 30 of the main cylinder or body 24 of the unit. At this moment, the retraction of the unit 18 is complete, and the parts occupy the positions shown in FIG. 2 of the drawings.

A study of FIGURES 2 and 3 of the drawings will make it evident that the amount of oil required for an expansion or power stroke of the unit 18 is many times greater than the amount of oil required for a retraction stroke. This is usual in telescopic cylinder units of this general type, and frequently the amount of oil required for the power stroke is as much as eight times as great as the amount required for a retraction stroke.

It follows also that retraction of the unit 18 can be accomplished only by moving a very large volume of oil out of the interior void in the unit 18. That is to say a large portion of oil used in expanding the unit 18 must be driven out of the unit during the retraction stroke. The speed with which retraction can take place, and the power required for retraction, depend in large measure upon the resistance of the discharge flow path for this oil.

The present invention represents a significant achievement in minimizing the resistance of the flow path for the ejection of the large body of oil within the central void of the unit 18. By reason of this, back pressure is minimized and the cylinder may be retracted quickly and easily. Note that the central void in the unit 18 shown in FIGS.

2 and 3 is in substantially open communication with the outlet passage 70. Oil may flow freely from one cylinder to the next through the large openings in the pistons 58 and 62, and the oil also may flow freely through the large opening 80 in the adapter 78.

Although only a single passage 70 in the head 68 has been illustrated, it will be evident that a plurality of these passages may be provided if it is desired to lower further the resistance of the flow path for the ejected oil.

The system for controlling the flow of hydraulic fluid to and from the telescopic cylinder unit 18 is indicated diagrammatically in FIG. 5 of the drawings. This system includes an oil tank or reservoir 96, a pump 98 connected to the oil tank 96, a control valve 100 connected to the pump, and a relief valve 102 interposed between the pump 98 and the control valve 100 to divert the flow from the pump directly into the oil tank 96 whenever the pressure at the control valve exceeds some predetermined value above the normal working range of the system. Suitable conduit means are provided for connecting the various components of the system together so that the hydraulic fluid may flow in the desired manner. It will be observed that the conduits 74 and 76 leading into the cylinder unit 18 are coupled to the control valve 100 of the system shown in FIG. 5.

The control valve 100 has three basic positions or conditions. In one of these, the hydraulic fluid delivered by the pump 98 is returned directly to the oil tank 96 so that the cylinder unit 18 will be idle or inactive. In a second condition of the control valve 100, the hydraulic fluid from the pump 98 is delivered through the valve 100 to the conduit 74, and hydraulic fluid may pass freely from the cylinder 18 through the conduit 76 and the valve 100 to the oil tank 96. This second condition of the control valve is that which causes expansion of the cylinder unit 18. A third condition of the control valve 100 is one in which the hydraulic fluid is delivered from the pump 98 through the control valve 100 into the conduit 76 leading to the retract side of the cylinder unit 18. This third condition of the valve control 100 also permits oil to flow freely from the cylinder unit 18 through the conduit 74 and the valve 100 to the oil tank 96. When the valve is in this condition, the cylinder unit 18 retracts.

The construction of the control valve 100 is shown best in FIGS. 6 through 11 of the drawings. When this valve is used in the hydraulic system, it is possible to cause the packer head 16 of the refuse-handling apparatus to move through the required strokes with very little attention from the operator of the apparatus.

The valve 100 includes a body designated generally by the numeral 104 which may be made up of as many pieces as required. The particular body construction 104 illustrated in the drawings is made up of three blocks or units 106, 108 and 110 suitably secured together, but this number may be varied as desired. Within the body 104, there is a main cylinder or bore 112 for slidably receiving a main piston or plunger designated generally by the numeral 114. A handle 116 (FIG. 6) is provided for manually shifting the plunger 114 along the bore 112.

Hydraulic fluid from the pump 98 may enter the valve 100 through an opening 116 communicating with a passageway 118 leading to two oil chambers 120 and 122 adjacent the main cylinder 112 of the device. The shape of the chambers 120 and 122 is not a critical factor. However, it is desirable that they be of such a nature that oil may pass readily from them through the main bore 112 of the valve whenever the spool or piston 114 is so positioned as to permit this action.

Hydraulic fluid passes from the control valve 100 to the oil tank 96 through an opening 124. This opening 124 communicates with a passageway 126 leading to a chamber 128 adjacent the main bore 112 of the device. The opening 124 also communicates with a radial passage 130 leading to another chamber 132 adjacent the

main bore 112. Hence, it will be seen that the oil may leave the valve 100 through the opening 124 if oil under pressure is admitted to either of the chambers 128 or 132.

In order for oil to flow to or from the control valve 100 through the conduit means 74 communicating with the cylinder unit 18, the body 104 of the control valve 100 is provided with a radial passage 134 communicating with an annular chamber 136 surrounding the main bore 112 of the device. This flow path is shown clearly in FIG. 10 of the drawings.

Similarly, oil may flow to or from the control valve 100 through the conduit 76 by passing through a radial passage 138 communicating with an annular chamber 140 surrounding the main bore 112. This flow path is illustrated in FIG. 11.

During operation of the hydraulic system, oil may flow between adjacent ones of the chambers 120, 122, 128, 132, 136 and 140, only to the extent permitted by a pair of reduced portions 142 and 144 in the piston 114 of the valve. The large portions 146, 148 and 150 of the plunger 114 are of substantially the same diameter as the bore 112. Whenever one of these large portions of the plunger 114 is located between adjacent ones of the chambers 120, 122, 128, 132, 136 and 140, it serves to block any flow of the oil between such chambers.

The position of the plunger 114 illustrated in FIG. 7 of the drawings is that which corresponds with the idle condition of the hydraulic circuit. Oil from the pump 98 enters the control valve 100 through the opening 116, and moves through the passage 118 into the chamber 122. Since the reduced portion 142 of the plunger 114 of the valve is located in the space between the chamber 122 and the adjacent chamber 128, the oil flows from the chamber 122 through the bore 112 to the chamber 128. The chamber 128 communicates with the outlet opening 124 through the passage 126, so that oil may flow directly from the chamber 128 into the conduit leading back to the oil tank or reservoir 96.

When it is desired to move the packer head 16 of the apparatus through a compaction cycle, the operator of the apparatus shifts the handle 116 of the control valve 100 to move the plunger 114 as far to the right (FIGS. 6-9) as is possible. This position is that in which the enlarged portion 150 of the plunger 114 abuts against the right end of the main bore 112 in the body 104, as illustrated in FIG. 8.

It will be observed that this movement of the plunger 114 brings the reduced portion 142 thereof into the space between the chambers 132 and 140, and also brings the reduced portion 144 thereof into the space between the chambers 120 and 136. This makes it possible for oil flowing into the opening 116 from the pump 98 to pass outwardly from the valve 100 through the conduit 74. It also makes it possible for the oil to flow into the valve unit 100 through the conduit 76, because the fluid chamber 140 leading to the conduit 76 is in open communication with the outlet opening 124 of the device. Thus, any oil which must be ejected from the cylinder unit 18 in order that the cylinder may expand will pass through the valve 100 and into the oil tank 96.

As the cylinder unit 18 expands, the pressure in the oil increases due to the load placed upon the hydraulic system when the refuse material is being packed between the packer head 16 and the rear wall of the compaction body. Hence, the cylinder unit 18 actually serves as a detector device for sensing the degree of compaction of the refuse material, because the oil pressure must exceed the back pressure offered by the refuse. When the back pressure reaches a certain predetermined value, it is desirable that the expansion stroke of the cylinder unit 18 should be terminated.

In order to accomplish this result automatically, the control valve 100 is provided with a small oil passageway 152 leading from the inlet opening 116 to a chamber 154

adjacent the right end of the main bore 112 in the body 104. An adjustable relief valve 156 normally blocks the passage 152, but when the pressure rises to some predetermined amount, the relief valve 156 opens to permit the flow of oil through the passage 152 and into the chamber 154. A needle valve 158 preferably is disposed between the relief valve 156 and the chamber 154.

As the pressure builds up in the chamber 154, the main piston or plunger 114 of the control valve 100 is urged to the left as viewed in FIGS. 7, 8 and 9. At this moment, there is a body of oil in the left end portion of the main cylinder or bore 112 which must be forced out of the cylinder by the moving plunger 114 through a small chamber 160 communicating with the left end of the bore 112 and a passage 162 leading from the chamber 160 to the outlet opening 124 in the body 104. However, there is a needle valve 164 in the passageway 162 which restricts the flow of the oil through the passage 162 so that the movement of the plunger 114 is a controlled movement, rather than a sudden shift to the left.

As the plunger 114 moves to the left from the position shown in FIG. 8 of the drawings, the inlet opening 116 connected to the pump 98 is uncoupled from the expand side of the cylinder unit 18 and coupled to the retract side thereof, while the outlet opening 124 connected to the oil tank 96 of the system is uncoupled from the retract side of the cylinder unit 18 and coupled to the expand side.

The manner in which this result is accomplished will be apparent from a comparison of FIGURES 8 and 9. Note that in FIG. 8 the reduced portion 144 of the plunger 114 is so located as to permit flow between the chambers 120 and 136, and that the reduced portion 142 of the plunger 114 is so located as to permit flow between the chambers 140 and 132. In this condition of the control valve 100, oil from the pump 98 may flow through the conduit 74 into the central void of the cylinder unit 18, and oil may flow from the cylinder unit 18 through the conduit 76 to the oil tank 96.

The flow pattern achieved when the plunger 114 is in the position shown in FIG. 9 is just the opposite of that achieved when the plunger is in the position shown in FIG. 8. In FIG. 9, the reduced portion 142 of the plunger 114 is so located that oil may flow from the chamber 122 into the chamber 140, and the reduced portion 144 of the plunger 114 is so located that the oil may flow from the chamber 136 into the chamber 132. Thus, the pump 98 is coupled to the conduit 76 leading to the retract side of the cylinder unit 18, while the conduit 74 leading from the expand side of the cylinder unit 18 is coupled with the oil tank 96 so that the oil within the central void of the cylinder unit 18 may be exhausted to the oil tank during the retract stroke of the cylinder unit.

It is an important feature of the invention that the plunger 114 of the control valve 100 stops automatically in the position shown in FIG. 9. The controlled movement of the plunger 114 to the left from the position shown in FIG. 8, due to the pressure of the oil in the chamber 154, continues only so long as the pressure in the inlet 116 is great enough to keep the relief valve 156 open. When the reduced portion 142 of the plunger 114 has moved far enough to the left to provide a substantial flow path between the chambers 122 and 140, the pressure at the inlet 116 drops far below that required for holding the relief valve 156 open, and there is no further tendency for the plunger 114 to move along the cylinder or bore 112. Thus, the position of the plunger 114 shown in FIG. 9 is a stable position, and the control valve 100 is effective automatically.

When the cylinder unit 18 has completed its contraction stroke, there is no room for additional oil inside the retraction passageways therein, and the pressure at the control valve 100 builds up again. When the pressure becomes great enough to open the relief valve 156, oil again flows from the inlet 116 through the passage 152 into

the chamber 154 at the right end of the bore 112. The increase in pressure at the right end of the bore 112 moves the plunger 114 on to the left from the position shown in FIG. 9 into the position shown in FIG. 7. This movement brings the reduced portion 142 of the plunger 114 into a position such that the oil may flow directly from the chamber 122 into the chamber 128, so as to couple the pump 98 with the oil tank 96. In this position of the parts, the cylinder unit 18 is idle, and the apparatus is ready for another compaction cycle whenever the operator desires to initiate such a cycle.

All the operator has to do to start another cycle is to move the handle 116 so as to shift the plunger 114 to the right from the position shown in FIG. 7 into the position shown in FIG. 8. During this movement of the plunger 114, the small amount of oil within the right end portion of the bore 112 may move out of the control valve 100 through a passage 166 having a needle valve 168 associated therewith.

After the operator has moved the plunger 114 from the position shown in FIG. 7 into the position shown in FIG. 8, he need do nothing further while the apparatus goes through its entire compaction cycle. That is to say, the packer head 16 moves back rearwardly until the refuse is compacted to a predetermined degree or pressure, and then the packer head 16 moves forwardly again and stops. During this period, the operator may give his full attention to other matters. He may leave the cab of the truck 2 to position other containers for cooperation with the front end loader mechanism 12, or he may drive the truck to some new pick-up location.

It will be observed also that the automatic cycle of the control valve 100 may be interrupted by the operator at any time. If some unusual occurrence should take place during either the compaction or the retraction stroke of the packer head 16 which would make it desirable to stop further movements of the packer head 16, this can be accomplished at once by shifting the handle 116 on the control valve 100 so as to return the plunger 114 to the position shown in FIG. 7. In this position of the plunger 114, the hydraulic system is idle.

The same automatic cycle required for compaction of the refuse material may be employed for ejecting the compacted refuse material from the rear end of the body 10. After the rear door of the body has been opened, the cycle may be initiated so that the packer head 16 will move rearwardly until the hydraulic cylinder unit 18 is fully expanded. At this point, pressure in the inlet 116 of the valve control 100 will rise sufficiently to overpower the relief valve 156 and cause retraction of the cylinder unit 18.

Another form of telescopic cylinder unit which may be used instead of the cylinder unit 18 in the compaction apparatus of FIG. 1 is illustrated in FIGS. 12 and 13 and is designated generally by the numeral 170. The unit 170 is made up of three cylinders or units 172, 174 and 176, but it will be understood that the number of stages employed may be varied if desired. The principles of construction and operation illustrated in FIGS. 12 and 13 may be adapted to units containing two or more stages of cylinders.

The large cylinder or base 172 is closed at one end by a closure member 178. The closure member 178 may be provided with a suitable fitting 180 through which oil may be admitted to the large void in the interior of the cylinder unit 170 for expanding the unit.

Near its opposite end, the large cylinder or base 172 is provided with a port 182 in its side wall communicating with a fitting 184 secured to the exterior of the cylinder 172. The fitting 184 provides a coupling for connecting a conduit 186 with the port 182 for retracting the cylinder unit 170.

The outer end portion of the cylinder 172 is similar in some respects to the construction described above in connection with FIGS. 2 and 3. A retainer 188 is threadedly connected with the end of the cylinder 172 and pro-

vides a stop preventing outward movement of an annular bushing 190. A spacer member 192 is held in place on the interior of the cylinder 172 by means of an O-ring type of retainer 194 and a body of suitable packing material 196 is disposed in the space between the spacer 192 and the bushing 190.

A port 198 is provided in the spacer 192 in position for communicating with the port 182 in the wall of the cylinder 172. The port 198 communicates with a longitudinally extending duct 200 in the inner face of the spacer 192 and also with a port 202 in the wall of the intermediate cylinder 174.

The intermediate cylinder 174 carries a piston 204 on its inner end. Throughout a major portion of the length of the intermediate cylinder 174, there is an internal cylindrical wall 206, held in spaced relation with respect to the interior surface of the cylinder 174 by suitable spacers such as those designated by the numerals 208 and 210 in the drawings. The space 212 between the intermediate cylinder 174 and the interior cylindrical wall 206 constitute an oil chamber or passageway in open communication with the port 202 in the wall of the cylinder 174.

At its outer end, the cylinder 174 is provided with a suitable retainer member 214, an annular bushing 216, a body of packing material 218, a spacer 220, and a retainer 222. These parts are similar to the corresponding parts carried by the upper end portion of the large cylinder or base 172 of the unit 170.

Oil may flow from the passageway 212 through a port 224 in the wall 206 and through an aperture 226 in the spacer 220. A longitudinal duct 228 in the spacer 220 permits the oil from the aperture 226 to pass to a piston 230 carried by the rear end of the small cylinder or ram 176 of the unit 170.

The outer end of the small cylinder or ram 176 is closed by a suitable plate or block member 232, which may be provided with any suitable means for facilitating the attachment of the cylinder unit 170 to the parts of the compaction apparatus with which it is to cooperate. A plate 234 is illustrated in FIG. 12 in this connection. It will be observed that the plate 234 is provided with a central aperture 236 by which the unit 170 may be pivotally connected to a part with which it is to cooperate. A similar plate 238 may be secured to the closure 178 for the large cylinder or base 172 of the unit 170.

The flow paths for the hydraulic fluid within the cylinder unit 170 now should be apparent. In order to expand the cylinder unit 170 from the condition shown in FIG. 13 into the condition shown in FIG. 12, oil is admitted through the opening 180 in the closure 178 for the left end of the large cylinder or base 172. This oil passes directly into the large internal void of the cylinder unit 170 and is available to expand the unit in the ordinary way.

When it is desired to retract the cylinder unit 170, oil is admitted under pressure through the conduit 186 and the port 182 in the side wall of the large cylinder or base 172, and the conduit 180 communicating with the interior void in the unit 170 is connected to the oil reservoir or tank. When the various passages in communication with the port 182 are filled with hydraulic fluid, the pressure begins to build up. The force exerted by this pressure will be a maximum against the piston 204 of the intermediate cylinder 174. This is so because the area of the piston 204 in contact with the oil is greater than the area of the piston 230 in contact with the oil. Consequently, the retraction cycle will begin by a movement of the piston 204 and the intermediate cylinder 174 to the left as viewed in FIG. 12.

After the intermediate cylinder 174 has moved all the way to the left, so as to bring the piston 204 into abutting relationship with respect to the closure 178, the hydraulic pressure will cause the small cylinder or ram 176 and its piston 230 to move to the left also. This movement brings the parts into the positions illustrated in FIG. 13.

It will be observed that, during retraction, the maxi-

mum force becomes available at the very beginning of the stroke. This feature has significance in connection with the compaction apparatus as a whole. The greatest force required during the retraction stroke is that required to accelerate the packer head 16 in a rearward direction and to disengage it from the charge of refuse in the body. The variations in force which will be realized during use of the cylinder unit 170 illustrated in FIGS. 12 and 13 conform very well to the actual requirements of the compaction apparatus in this respect.

It also will be observed in connection with FIG. 12 that the large central void within the unit 170 is in open and free communication with the conduit 180. Hence, during retraction of the unit 170, the large body of oil in the central void may pass freely out through the conduit 180, and the back pressure developed during the retraction stroke will be minimized.

Although certain embodiments of the invention have been illustrated and described in detail, variations and modifications will be obvious to persons skilled in the art. In particular, it will be apparent that various elements of the illustrated constructions are capable of advantageous use in other combinations. For example, the automatic sequence valve shown in FIGS. 6 to 11 need not be used to control a telescopic cylinder unit but may be used in combination with a single-stage, piston-type, double-acting cylinder unit, if desired. It is intended, therefore, that the foregoing description be considered as exemplary only and that the scope of this invention be ascertained from the following claims.

We claim:

1. Compaction apparatus comprising a body, a packer head movable back and forth in said body, a double-acting telescopic cylinder unit connected at one end thereof to said body and connected to the other end thereof to said packer head for moving said head, said cylinder unit comprising a plurality of cylinders having large central openings therein in free communication with each other, and fluid conduit means connected to said ram end of said cylinder unit for delivering fluid to the interior of the cylinders, the unit during expansion strokes thereof, and separate fluid conduit means for delivering fluid to the space between the cylinders and out of communication with the interior thereof for causing retraction strokes of the cylinders, said cylinder unit being so constructed that a large volume of fluid may pass freely into the interior thereof during expansion strokes and pass freely from the interior thereof during retraction strokes whereby back pressure during retraction strokes is minimized.

2. A double-acting telescopic cylinder unit comprising a plurality of cylinders mounted for telescoping movements relative to each other, said cylinders having large central openings therein in free communication with each other so that a large volume of hydraulic fluid may fill said openings rapidly to expand the cylinder unit, conduit means connected to the exposed end of an endmost cylinder in the cylinder unit to deliver fluid to or from the central opening therein, said cylinders being mounted with respect to each other so as to leave closed spaces between the walls of adjacent cylinders into which hydraulic fluid may be forced to cause retraction of the cylinder unit, and conduit means fixed to said endmost cylinder and communicating with the space between said endmost cylinder and the adjacent cylinder in the unit at a location near the opposite end of said endmost cylinder.

3. A double-acting telescopic cylinder unit comprising a plurality of cylinders mounted for telescoping movements relative to each other, said cylinders having large central openings therein in free communication with each other so that a large volume of hydraulic fluid may fill said

openings rapidly to expand the cylinder unit, conduit means connected to the exposed end of the largest endmost cylinder in the cylinder unit to deliver fluid to or from the central opening therein, said cylinders being mounted with respect to each other so as to leave closed spaces between the walls of adjacent cylinders into which hydraulic fluid may be forced to cause retraction of the cylinder unit, and conduit means fixed to and extending along the exterior of said endmost cylinder and communicating with the space between said endmost cylinder and the adjacent cylinder in the unit at a location near the opposite end of said endmost cylinder.

4. A double-acting telescopic cylinder unit comprising a plurality of cylinders mounted for telescoping movements relative to each other, said cylinders having large central openings therein in free communication with each other so that a large volume of hydraulic fluid may fill said openings rapidly to expand the cylinder unit, conduit means connected to the exposed end of the smallest endmost cylinder in the cylinder unit to deliver fluid to or from the central opening therein, said cylinders being mounted with respect to each other so as to leave closed spaces between the walls of adjacent cylinders into which hydraulic fluid may be forced to cause retraction of the cylinder unit, and conduit means fixed to and extending through the interior of said endmost cylinder and communicating with the space between said endmost cylinder and the adjacent cylinder in the unit at a location near the opposite end of said endmost cylinder.

5. A double-acting telescopic cylinder unit comprising a large cylinder having a large central opening therein, means closing the inner end of said large cylinder, annular means fixed to the outer end of said large cylinder and projecting inwardly a short distance from the inner wall of said large cylinder, a ram cylinder mounted for sliding movement relative to said annular means and having an annular piston on its inner end in sliding contact with the inner wall of said large cylinder, said ram cylinder having a large central opening therein in free communication with the large central opening in said large cylinder and being closed at its outer end, said ram cylinder also having a port in its wall near the inner end thereof at a location between said piston and said annular means, conduit means extending from the outer end of said ram cylinder through the central opening therein to said port, and conduit means connected to the outer end of said ram cylinder for delivering hydraulic fluid to or from the large central opening in said ram cylinder and for delivering hydraulic fluid to or from said conduit means in said ram cylinder.
